UNITED STATES PATENT OFFICE.

REUBEN WILLIAM TARRANT, OF LONDON, ENGLAND.

RAILWAY SIGNALING.

1,322,651.

Specification of Letters Patent. Patented Nov. 25, 1919.

Application filed September 21, 1916. Serial No. 121,370.

To all whom it may concern:

Be it known that I, REUBEN WILLIAM TARRANT, a subject of the King of Great Britain, and resident of 26 Voltaire road, 5 Clapham, London, England, have invented certain new and useful Improvements in Railway Signaling, of which the following is a specification.

In railway track-circuit systems for the 10 electric control of signals or the like, wherein in the respective rails of a block-section of the line are electrically connected together at one end (which may be termed the battery end) of the section through a source of current and at the opposite end (which may be termed the track-relay end) through the 15 winding of a track-relay, the bridging of the rails at any intermediate point in the length of the block-section by an axle and pair of wheels (or other electric conductor which 20 materially reduces the resistance normally existing in the track-circuit) has for effect, while cutting out the track-relay by short-circuiting the source of energy, to increase 25 for the time being the flow of current through said source. The extra expenditure of current thus caused performs no useful work and is entirely wasteful, the loss being especially disadvantageous when a block- 30 section (such as a siding or station-bay for example) remains occupied by a train or vehicle during the night or other comparatively lengthy period.

The object of the present invention is not 35 only to prevent automatically this waste of energy during the time the block-section is occupied by a train, but to enable the expenditure of current to be actually reduced, during such time, to an amount considerably 40 below that which is normally consumed when the section is unoccupied. For this purpose I provide, in connection with a railway electric track-circuit and track-relay for controlling a signal or the like, an electrically-operated automatically-acting current-economizing device comprising a resistance 45 higher than that normally existing in the track-circuit, said resistance being so connected as to be effectively included in the 50 track-circuit so long only as the block-section to which said circuit appertains is occupied by a railway train or vehicle.

The electrically-operated device just mentioned, which will hereinafter be termed the 55 economizer - relay, comprises electromagnet-

windings whereof one is constantly connected in circuit with the track-rails while another serves as the current-economizing resistance, and an armature operating as the result of the energization of said windings 60 and adapted to control a switch whereby the circuit-connections of said windings are so governed that, on the battery (or other source of energy) which supplies current to the track-rails being short-circuited across 65 the rails (for example, in consequence of the presence in the block-section of a train or vehicle), the current-economizing resistance will be rendered effective but will be caused to become inoperative when such short- 70 circuiting ceases.

My invention will be better understood by referring to the accompanying drawings. Figure 1 is a diagram showing an arrangement of the electric connections wherein the 75 economizer - relay switch closes a circuit when in its normal position only, and Fig. 2 is a similar diagram showing an arrangement wherein said switch closes different circuits in its normal and abnormal positions 80 respectively. In Figs. 1 and 2, all parts are shown as occupying their normal positions.

Figs. 3 to 5 show a constructional form of the economizer-relay adapted for use with connections as shown both in Fig. 1 85 and in Fig. 2. Fig. 3 is a plan view, partly in section and with the cover removed; Fig. 4 is an end elevation looking from the lower side of Fig. 3, with the cover in section; and Fig. 5 is a side elevation looking 90 from left to right in Figs. 3 and 4, with the cover and part of the bed-plate in section.

Corresponding parts are denoted by similar reference symbols throughout the drawings. 95

Referring first to Figs. 1 and 2, *a* and *b* are the track-rails of an insulated block-section of the road, entrance to which is governed by a signal *c* whereof the electric controlling apparatus *d* is supplied with current 100 from a battery (or other source of power) *e* the circuit of which is controlled by a switch *f* operated by the armature *g* of the usual track-relay *h*; the opposite ends of the relay-winding being connected to the respective track-rails *a* and *b* so that, the track-circuit being normally closed and the relay energized, the armature *g* is held in the attracted position wherein it closes the switch *f*. 105

Current is supplied to the track-circuit, at the end of the block-section remote from the signal *c* and relay *h*, by a battery (or other source of power) *j*, and at this battery-end of the section is installed the economizer-relay, which comprises two distinct electromagnets *k* and *m* whereof the cores are shown in the diagrams (for the sake of simplicity and clearness) as arranged for magnetic operation at one pole only in each. It is to be understood, however, that each of these cores might be magnetically operative at both ends.

The core of the electromagnet *k* is shown as having pivotally attached to its operative pole an extension *n* constituting a polarized armature for the economizer-relay, this armature *n*, which tends to assume and normally occupies the unattracted position wherein it is shown, being adapted, when magnetized by the core to which it is attached, to approach the adjacent pole of the core of the electromagnet *m*. The armature *n* serves to operate a switch-tongue *o* which (in both Figs. 1 and 2) it normally permits to rest in contact with a terminal *p* so as to establish an electrical connection which is broken when the armature *n* assumes the attracted position. In the arrangement illustrated in Fig. 1 the switch-tongue *o*, when lifted off the terminal *p*, does not establish any other connection; whereas in the arrangement illustrated in Fig. 2, the switch-tongue *o*, when lifted off the terminal *p*, establishes connection with a terminal *r*.

The electromagnet *k* has two windings *s* and *t* whereof *s* is the so-called main winding and *t* the current-reducer or economizer-winding. The electromagnet *m* has only the single so-called neutralizing-winding *v*. The main winding *s*, although constantly included effectively in the track circuit and therefore always energized, is only adapted to magnetize the armature *n* strongly enough to cause displacement of the armature from normal position when said winding *s* is energized by current of a value greater than that of the current normally flowing in the track-circuit. The economizer-winding *t*, which is adapted to produce in the armature *n* polarity of the same sign as that produced by the main winding *s*, is normally inoperative but is of such resistance that, when connected in series with the track-circuit by the action of the switch *o*, it reduces the current flowing therein to less than its normal value. The neutralizing-winding *v* is normally inoperative but, when energized in consequence of the action of the switch *o*, is adapted to create a magnetic field of a strength almost but not quite equal to that produced by the concurrent energization of the windings *s* and *t*, the field produced by the winding *v* tending to repel the

armature *n* from the pole of the electromagnet *m*.

In the arrangement illustrated in Fig. 1, the electric connections of the economizer-relay are as follows: One pole of the track-circuit battery *j* is connected by a wire 11 to the track-rail *b*, and the other pole of the battery is connected by a wire 12 to one end of the main winding *s* the opposite end of which is connected by a wire 13 to the switch-tongue *o*. The contact *p* is connected by a wire 14 to the track-rail *a*. The opposite ends of the economizer-winding *t* are connected by wires 15 and 16 to the wires 13 and 14 respectively; and similarly, the opposite ends of the neutralizing-winding *v* are connected by wires 17 and 18 to the wires 13 and 14 respectively.

It will be observed that normally (*i. e.* when all the parts are in the positions indicated and no train is in the block-section) all the current from battery *j* passes through the main winding *s* and switch *o*; the windings *t* and *v*, both of which are of higher resistance than *s* and are connected each in series therewith but in a shunt across the switch *o*, remaining normally deenergized.

The action of the apparatus as shown in Fig. 1 is as follows:

On a train entering the block-section, the track-circuit battery *j* is short-circuited in consequence of the bridging of the track-rails *a*, *b* by the wheels and axles of the train, and the track-relay *h* being thus cut out its armature *g* falls, the circuit of the signal-controlling battery *e* is broken at the switch *f*, and the signal *c* (which normally stands at "line clear") is put to "line blocked". All this is as usual in track-circuit working.

At the economizer-relay, the short-circuiting of the battery *j* causes a momentary rush of current through the main winding *s*, current passing from one pole of the battery, by wire 12, winding *s*, wire 13, switch *o*, contact *p*, wire 14, rail *a*, the wheels and axles of the train, rail *b*, and wire 11, back to the other pole of battery *j*, with the result that the magnetization of the armature *n* is so increased that the armature approaches the pole of the electromagnet *m*. This movement of the armature, by lifting the switch *o* from the contact *p*, renders both the windings *t* and *v* effective; part of the current now passing from one pole of battery *j*, by wire 12, winding *s*, wires 13 and 15, winding *t*, wires 16 and 14, rail *a*, the wheels and axles of the train, rail *b*, and wire 11, back to the other pole of the battery, while at the same time, part of the current (after flowing through the winding *s*) passes by wires 13 and 17, winding *v*, and wire 18, to wire 14. Hence, the neutralizing-winding *v* being energized, the magnetic force which holds the armature *n* in the attracted position is so far counteracted by the repulsive force ex-

105

115

120

125

130

erted by the winding v that the armature is only just prevented from dropping back to normal position.

It will be seen that a result of the windings t and v being thrown into the circuit is that the value of the current flowing therein is reduced below the normal to an extent corresponding to the magnitude of the extra resistance thus introduced, such reduction of current continuing so long as the train remains in the block-section.

When the train leaves the block-section, current again passes through the track-relay h and, the switch f being consequently closed, the signal c is returned to "line clear" in the usual manner. At the economizer-relay, the reinterposition in the track-circuit of the resistance due to the track-relay winding h has for effect to so reduce the value of the current flowing through the windings s , t and v that the armature n ceases to be attracted sufficiently to remain in the abnormal position to which it had been brought. Hence the armature falls back to normal position, the switch o reestablishes connection with the contact p , and normal conditions are therefore restored throughout the system.

In the arrangement illustrated in Fig. 2, the electric connections of the economizer-relay are as follows: One pole of the track-circuit battery j is connected by a wire 19 to one end of the main winding s the opposite end of which is connected by a wire 20 to the track-rail a . The other pole of the battery j is connected by a wire 21 to one end of the economizer-winding t the opposite end of which is connected by a wire 22 to the track-rail b . This latter pole of the battery j is also connected by a wire 23 to the contact p , while the switch o is connected by a wire 24 to the wire 22. The contact r is connected by a wire 25 to one end of the neutralizing-winding v the opposite end of which is connected to the wire 19. It will be observed that normally (i. e. when all the parts are in the positions indicated and no train is in the block-section) all the current from battery j passes through the main winding s ; both ends of the winding t being then connected to the same pole of battery j and the circuit of the winding v being broken at the contact r , so that the windings t and v are both normally deenergized.

The action of the apparatus as shown in Fig. 2 is as follows:

On a train entering the block-section, the track-circuit battery j is short-circuited in consequence of the bridging of the track-rails a , b by the wheels and axles of the train, the track-relay h is cut out, its armature g falls, the circuit of the signal-controlling battery e is broken at the switch f and the signal c is put to "line blocked", all as already described with reference to Fig. 1.

At the economizer-relay, the short-circuiting of the battery j causes a momentary rush of current through the main winding s , current passing from one pole of the battery, by wire 19, winding s , wire 20, rail a , the wheels and axles of the train, rail b , wires 22 and 24, switch o , contact p , and wire 23, back to the other pole of battery j , with the result that the magnetization of the armature n is so increased that the armature approaches the pole of the electromagnet m . This movement of the armature breaks the switch-connection at o , p and establishes a switch-connection at o , r and thus throws both the windings t and v into circuit; part of the current now passing from one pole of battery j , by wire 19, winding s , wire 20, rail a , the wheels and axles of the train, rail b , wire 22, winding t , and wire 21, back to the other pole of the battery, while at the same time part of the current passes from wire 19, by winding v , wire 25, contact r , switch o , and wire 24, to wire 22, and thence through winding t and wire 21 to the battery. Hence, the neutralizing-winding v being energized, the magnetic force which holds the armature n in the attracted position is so far counteracted by the repulsive force exerted by the winding v that the armature is only just prevented from dropping back to normal position.

It will be seen that, as already stated with reference to Fig. 1, a result of the windings t and v being thrown into the circuit is that the value of the current flowing therein is reduced below the normal to an extent corresponding to the magnitude of the resistance thus introduced, such reduction of current continuing so long as the train remains in the block-section.

When the train leaves the block-section, current again passes through the track-relay h and the signal c is returned to "line clear" as described with reference to Fig. 1. At the economizer-relay, the re-interposition in the track-circuit of the resistance due to the track-relay winding h has for effect to so reduce the value of the current flowing through the windings s , t , and v that the armature n ceases to be attracted sufficiently to remain in the abnormal position to which it had been brought. Hence the armature falls back to normal position, the switch o breaks connection with the contact r and re-establishes connection with the contact p , and normal conditions are therefore restored throughout the system.

Referring now to the constructional form of the economizer-relay illustrated in Figs. 3, 4 and 5, k and m are the two electromagnets already described with reference to the diagrams Figs. 1 and 2. These electromagnets are mounted alongside one another with their respective cores k' and m' (which are formed each of a straight cylindrical iron

- bar) parallel and horizontal; the core m' of the electromagnet m having coiled about it the neutralizing-winding v while the core k' of the electromagnet k has coiled about it
- 5 the main winding s and, superposed thereon, the current-reducer or economizer-winding t . The ends of the core m' project beyond the bobbin of the electromagnet m and are fixed in brackets 26, 27 upstanding from
- 10 a brass plate 28 which carries both electromagnets and which is mounted on top of a cast iron bed-plate 29 serving to support the entire structure of the relay. The core k' is adapted to rotate through a small angle
- 15 within the bobbin of the electromagnet k , the ends of the core being supported by axial pivot-pins 30, 31 fixed in brackets 32, 33 also upstanding from the plate 28.
- The rotary core k' has fast upon its ends
- 20 a pair of iron arms n^1 , n^2 which conjointly constitute the economizer-relay armature; the free end-portions 34, 35 of these arms extending across and beneath the projecting end portions of the fixed core m' and at such distance therefrom that magnetization of the core k' and armature-arms n^1 , n^2 will cause the core to rotate in consequence of the free ends of the arms then concurrently rising (in opposition to gravity) from their
- 25 normal position so as to approach the adjacent ends of the core m' and assume the abnormal or attracted position wherein they are shown in Figs. 4 and 5. In order to increase the efficiency of the magnetic field,
- 30 the upper side of the free ends of the armature-arms n^1 , n^2 are of inverted V-shape in cross section as at 34, 35 and enter transverse notches of corresponding shape on the under-side of the core m' , as indicated in Fig. 5.
- 35 40 o is the blade of the economizer-relay switch, which extends alongside of and parallel to the armature-arm n^1 and is pivoted at 36 in a bracket mounted upon but insulated from the plate 28; the blade o having, at the opposite side of the pivot 36, a laterally-cranked extension 37 which is presented beneath an adjustable tappet-screw carried by a corresponding extension 38 of the arm n^1 . The vibratory movement of
- 45 the switch-blade o is limited by lower and upper cross-pins p and r of metal, and when all the parts are in normal position, the blade o rests upon the lower cross-pin p which is carried by a brass bracket 39 mounted
- 50 upon but insulated from the plate 28; this cross pin p , which is always connected electrically, serving the same function as the contact p in Fig. 1 or in Fig. 2 as the case may be. When the free ends 34, 35 of the
- 55 60 armature-arms n^1 , n^2 rise to their abnormal or attracted position, the switch-blade o encounters the upper cross-pin r , which is carried by a brass bracket 40 mounted upon the plate 28 but insulated therefrom and from the bracket 39 and cross-pin p . The cross-

pin r may either be a mere stop, or may be electrically connected and serve the same function as the contact r in Fig. 2.

The electromagnets k and m , with their cores and the armature-arms n^1 and n^2 , the switch blade o and cross-pins p and r , are all inclosed within the removable cover 41. The bed-plate 29 carries a row of insulated terminals 42, 43, 44 and 45 through which the various leads are connected, on the one hand to the windings s , t and v , to the switch-blade o , and to the contact-pins p and r , and on the other hand to the poles of the battery and to the track-rails, so as to provide connections similar to those described with reference either to Fig. 1 or to Fig. 2.

With regard to the function performed by the neutralizing-winding, it is to be observed that this is of great practical importance in view of the continual fluctuations of current which are liable to occur in a track-circuit in consequence, chiefly, of variations in the ohmic value of the rail-to-rail or ballast-resistance; the employment of the neutralizing-winding, whereof the resistance can be adjusted with any degree of precision relatively to that of the current-reducer or economizer-winding, enabling the "fall-away point" (i. e. the current-condition upon which the return of the economizer relay armature to normal position depends) to be determined and kept within the necessary limits notwithstanding the occurrence of wide and sudden variations in the ballast-resistance. For this purpose the current-reducer and neutralizing windings are so wound relatively to one another as to be adapted to produce conjointly, when energized, a magnetic condition in the armature closely approaching neutrality or depolarization, whatever increase or decrease may at any time occur in the current flowing through the windings. At the same time the main winding is given only a few turns, so that its magnetic field, although capable of moving the armature from normal position on the occurrence of a rush of current such as follows on a train entering the block-section, will be unable to retain the armature in abnormal position with any accidental increase of current (due to, say, temporary reduction of the ballast-resistance) to an extent even sufficient to bring up the current-value to almost that strength which would cause the armature to move from normal position. It will thus be seen that the determination of the "fall-away point" by means of the neutralizing-winding enables the magnetic control of the economizer-relay switch to be effected with almost any desired degree of precision.

What I claim is:—

1. An electrically operated device for economizing current in a track-circuit, said device comprising a stationary piece of soft

- iron, a magnet having a core connected to an armature movable relatively to said stationary piece and constantly tending to recede therefrom, two windings coiled about 5 the core of the magnet and both adapted to produce magnetic polarities of the same sign in said armature, one of said windings being constantly included effectively in the track-circuit and being of relatively low resistance while the other winding has a resistance higher than that normally existing in the track-circuit, and a switch actuated by the movement of said armature for so controlling the circuit-connections of the several 10 windings that the higher resistance winding magnet will be effectively included in the track-circuit so long only as the track-circuit battery is short-circuited across the track rails.
- 20 2. An electrically-operated device for economizing current in a track-circuit, said device comprising two electromagnets, the core of the first magnet having a stationary pole-piece while the core of the second magnet is connected to an armature movable relatively to said stationary pole-piece and constantly tending to recede therefrom when said track is unoccupied, two windings coiled about the core of the second magnet 25 and both adapted to produce magnetic polarities of the same sign in said armature, one of said windings being constantly included effectively in the track-circuit and being of relatively low resistance while the other winding has a resistance higher than that normally existing in the track-circuit, a single winding coiled about the core of the first magnet, the resistance of said winding being almost equal to the conjoint resistances of the other two windings, said single winding being adapted to produce a magnetic field tending to repel said armature in opposition to the magnetic influence exerted by the two windings of the second magnet, and a switch actuated by the movement of said armature for so controlling the circuit-connections of the several windings that the higher-resistance winding of the second magnet will be effectively included in the track-circuit so long only as the track-circuit battery is short-circuited across the track-rails.
- 30 3. An electrically-operated device for economizing current in a track-circuit, said device comprising two electromagnets, the core of the first magnet having a stationary pole-piece while the core of the second magnet is connected to an armature movable relatively to said stationary pole-piece and constantly tending to recede therefrom when said track is unoccupied, two windings coiled about the core of the second magnet 35 and both adapted to produce magnetic polarities of the same sign in said armature, one of said windings being constantly included effectively in the track-circuit and being of relatively low resistance while the other winding has a resistance higher than that normally existing in the track-circuit, a single winding coiled about the core of the first magnet, the resistance of said winding being almost equal to the conjoint resistances of the other two windings, said single winding being adapted to produce a magnetic field tending to repel said armature in opposition to the magnetic influence exerted by the two windings of the second magnet, and a switch actuated by the movement of said armature for so controlling the circuit-connections of the several windings that the higher-resistance winding of the second magnet will be effectively included in the track-circuit so long only as the track-circuit battery is short-circuited across the track-rails.
- 40 4. An electrically-operated device for economizing current in a track-circuit, said device comprising two electromagnets, the core of the first magnet having a stationary pole-piece while the core of the second magnet is connected to an armature movable relatively to said stationary pole-piece and constantly tending to recede therefrom when said track is unoccupied, two windings coiled about the core of the second magnet 45 and both adapted to produce magnetic polarities of the same sign in said armature, one of said windings being constantly included effectively in the track-circuit and being of relatively low resistance while the other winding has a resistance higher than that normally existing in the track-circuit, a single winding coiled about the core of the first magnet, the resistance of said winding being almost equal to the conjoint resistances of the other two windings, said single winding being adapted to produce a magnetic field tending to repel said armature in opposition to the magnetic influence exerted by the two windings of the second magnet, and a switch actuated by the movement of said armature and adapted to establish connection with each of two electric contacts alternatively, in the one case for rendering operative only the low resistance winding of the second magnet and in the other case for rendering operative said low-resistance winding, the higher-resistance winding of said second magnet, and the winding of the first magnet.
- 50 5. Electrically operated apparatus for reducing below the normal the expenditure of current in a block of an electrical block signaling system when said block is occupied by a train, said means comprising an electromagnet-winding constantly included effectively in the track-circuit, an armature subject to the magnetic influence of said winding and movable thereby from normal to attracted position only when said wind- 55
- 60
- 65

ing is energized by current having a value greater than that of the current normally flowing in the track-circuit, a second electromagnet-winding adapted to coöperate with the first-mentioned winding in retaining said armature magnetically in its attracted position, the resistance of said second winding being higher than that normally existing in the track-circuit, a third 10 electromagnet-winding whereof the resistance is almost equal to the conjoint resist-

ance of the other two windings and which is adapted to create a magnetic field tending to repel said armature from its attracted position, and a switch controlled by said 15 armature and adapted, when moved from normal position, to bring about effective inclusion of the second winding in the track-circuit and energization of the third winding.

REUBEN WILLIAM TARRANT.
